UNITED STATES PATENT OFFICE.

GEORGE OLDHAM, OF YOUNGSTOWN, OHIO.

DESIGN FOR SHOE-CLASPS.

Specification forming part of Design No. 5,151, dated August 1, 1871.

To all whom it may concern:

Be it known that I, GEORGE OLDHAM, of Youngstown, in the county of Mahoning and State of Ohio, have invented and produced a new and original Design for a Shoe-Clasp; and I do hereby declare the following to be a full, clear, and exact description of the same, reference being had to the accompanying drawing forming part of this specification, and which fully illustrates my design.

Figure 1 is a top view of the shoe-clasp, and Fig. 2 is a side view of the same.

Similar letters of reference in the accompanying drawing indicate corresponding parts.

My invention consists in making the clasps of two curved plates, A B, each provided at its

outer end with a hook, c, as shown. The plate A is provided, also, with a hook, D, at its inner end, while the plate B terminates with a straight edge, but has a series of transverse slots, E E E, arranged as shown in Fig. 1. The outer corners of the plates are rounded off as represented, while the inner corners are square.

Having thus described my invention, what I claim as new, and desire to secure by Letters Patent, is—

The design for a shoe-clasp, as shown.

GEORGE OLDHAM.
